DOZIER FINLEY

by Charles S. Evans
HIS ATTORNEY.

UNITED STATES PATENT OFFICE

DOZIER FINLEY, OF BERKELEY, CALIFORNIA, ASSIGNOR TO THE PARAFFINE COMPANIES, INC., OF SAN FRANCISCO, CALIFORNIA, A CORPORATION OF DELAWARE

COVERING FOR STAVED PIPES

Application filed August 10, 1927. Serial No. 212,008.

My invention relates to a pipe covering and the broad object of my invention is to provide binding means for pipes which will permit the ready application of a pipe covering thereto.

Another object of my invention is to provide recesses on the surface of the pipe, to permit the seating of the binding means therein.

10 Another object of my invention is to seat the binding means within the recesses approximately flush with the surface of the pipe.

Other objects of the invention together with the foregoing will be set forth in the following description of the preferred embodiment of means for practicing my invention and which is illustrated in the drawings accompanying and forming part of the specification. It is to be understood that I do not limit myself to the showing made by the said description and drawings, as I may adopt variations of my preferred form within the scope of my invention as set forth in the 25 claims.

Referring to the drawings:

Figure 1 is a longitudinal, cross sectional view of the pipe, pipe covering and binding.

Figure 2 is a sectional view showing a 30 binding wire seated in a recess in the surface of the pipe.

Figure 3 is a plan view illustrating the manner in which the binding means is fastened.

A pipe designed for underground work is 35 preferably covered by means of an insulating covering in order to protect it. In many cases, staved pipes are used and it is then necessary to apply a binding in order to hold them together. Upon application of the covering, it is apparent that a smooth surface is difficult to obtain, since the binding means which rests on the surface of the pipe will project into the covering and cause ridges therein.

45 In terms of broad inclusion my invention comprises the provision of recesses and/or grooves in the surface of a pipe, in order that binding means, such as a binding wire and clamping anchor, can seat therein and lie approximately flush with the surface thereof;

so that a covering can be smoothly placed thereon. It is preferred to provide recesses deep enough to completely seat the binding means, rather than to have them project above the surface.

55

More specifically my invention comprises a wood staved pipe 2, the surface of which is preferably provided with a continuous spiral groove or recess 3. A binding wire 4 is wound around the pipe and is seated within the 60 groove, and the top thereof is approximately flush with or below the outer surface of the pipe, so that a covering 6 can be smoothly wound therearound. Although in the preferred embodiment of my invention, a spiral 65 groove is provided, it is obvious that the spirit of the invention can be carried out with any other method of binding, provided that the means are seated in the outer surface of the pipe. In order to prevent the binding means, 70 which may be of metal, from corroding due to moisture which might accumulate in the wood, it is preferred to provide a layer 7 of insulating material such as asphalt, tar or bitumen between it and the pipe, as is shown 75 in Figure 2.

In Figure 3 is shown the method of fastening. Near the end of the pipe a wider recess 8 is provided, so that it can accommodate several loops of wire lying adjacent to 80 each other. This groove leads into a deeper recess 9 in which is seated the anchor 11 having prongs 12 projecting into the wood and prongs 13 bent over the loops to secure and fix the strand of wire. The end of the wire 85 is bent back along the anchor and is secured in recess 9 by means of a staple 14.

From the above, it can be seen that if a covering is applied over the pipe, there will be no projections on the surface thereof, to 90 prevent the smooth application of the covering thereto.

I claim:

1. A pipe having a recess in the surface thereof and a second preformed recess communicating therewith, binding means seated in the first recess, and means seated in the second recess for clamping said binding means.

2. A pipe having a groove extending 100

around the surface thereof and a preformed recess communicating therewith, a binding wire seated in said groove, and means seated in said recess for clamping the wire.

5 3. A pipe having a continuous substantially helical groove extending around the surface thereof and a preformed recess communicating therewith, a binding wire seated in said groove, and means seated in said recess for clamping the wire.

10 4. A pipe having a continuous substantially helical groove extending around the surface thereof, said groove forming an enlarged recess encircling the pipe adjacent the 15 end thereof, a binding wire seated in said groove and coiled in a plurality of loops lying in said enlarged recess, and means seated in said recess for clamping the loops.

15 5. A pipe having a continuous substantially helical groove extending around the surface thereof, said groove forming an enlarged recess encircling the pipe adjacent the end thereof and said recess communicating with a second recess in the pipe, a binding 20 wire seated in said groove and coiled in a plurality of loops lying in said enlarged recess, and means seated in the second recess for clamping the loops.

25 In testimony whereof, I have hereunto set
30 my hand.

DOZIER FINLEY.
